HYDRAULIC MOTOR

Arthur L. Parker, Cleveland, Ohio, assignor to
 The Parker Appliance Company, Cleveland,
 Ohio, a corporation of Ohio

Application March 31, 1941, Serial No. 386,219

1 Claim. (Cl. 60—97)

This invention relates to improvements in hydraulic motors, and more particularly to a type of motor in which fluid under pressure supplied from an outside source will impart limited rotation to the motor shaft.

An object of this invention is to provide a motor of the type described in which the vane against which the fluid pressure acts is integral with the motor shaft.

Another object is to provide a motor of the type described in which a constant torque is transmitted to the motor shaft.

Another object is to provide a motor in which the vane has a plurality of wall sections each in communication with a separate pressure chamber and means for admitting fluid under pressure to each chamber selectively, or to any combination of chambers simultaneously, whereby, to obtain varying torques of predetermined magnitudes upon the motor shaft.

The above and other objects of the invention will in part be obvious and will be hereinafter more fully pointed out.

In the accompanying drawing:

Figure 1 is a top view, in section, taken along the line A—A of Figure 2.

Figure 2 is a side view in section, taken along the line B—B of Figure 1.

Figure 3 is a diagrammatic view showing one form of piping arrangement for supplying fluid under pressure.

In the invention as illustrated, there is provided cylindrical housing or casing 10 having a bore 11 and a closed end wall 12, and being closed at the opposite end by a closure plate 13 bolted to the casing as at 14. A suitable gasket 15 assures a leakproof joint. The closed end wall 12 includes a projecting portion 16 which is recessed as at 17 and in which is mounted a bushing 18. The closure plate 13 also includes a centrally located projecting portion 19 having a central bore 20 in which is mounted another bushing 21. A shaft 22 is mounted within the casing and is journaled in the bushings 18 and 21 as shown. A thrust bearing 23 is provided in the recessed lower end of the shaft 22 for taking end thrust thereon.

Keyed to the outer end of the shaft 22 by means of the keys 23a is a flange 24 with spaced bolt holes 25 to allow proper connection to the part which it is desired to rotate by means of the motor. A suitable bushing 26 is provided within the counterbore 27 of the extension 19 for journaling the hub extension 24a of the flange 24. Intermediate the bushings 21 and 26 there is provided

any suitable packing means 28 for sealing against the leakage of fluid from within the casing 10.

Intermediate the ends of the shaft 22 and formed integrally therewith there is a circular flange portion 29. This flange portion is preferably spaced a greater distance from either of the end wall portions 12 or 13 so as to divide the bore 11 into two chambers 30 and 31 of unequal length. In the present instance as shown in Figure 2 the flange 29 is spaced closer to the end wall 12 than to the end wall 13 so that the chamber 30 is greater than the chamber 31. An annular packing 32 is provided in a groove 33 so as to prevent the leakage of fluid from the chamber 30 to the chamber 31 or vice versa.

Also formed integrally with the shaft 22 is a radially projecting rib or vane 34 which extends from the end wall 12 to the end wall 13.

Rigidly mounted as at 35 within the chamber 30 and extending from the end wall 13 to the flange 29 of the shaft 22 is the segmental portion 36. This segmental portion extends radially from the casing wall 10 to the shaft 22 and thus in conjunction with the vane 34 divides the chamber 30 into the chambers 30a and 30b. A bore passage 37 establishes communication between the chamber 30—a and a threaded outlet 39 in the casing 10. A similar passage 38 establishes communication between chamber 30—b and a threaded outlet 40 in the casing 10. To these threaded outlets 39 and 40 are connected fluid conduit lines 41 and 42 which lead to a suitable reversing valve 43 of conventional design.

A second segmental portion 44 similar to the segmental portion 36 is mounted within the chamber 31 and divides it into the chambers 31—a and 31—b in a like manner. Passages 45 and 46 establish communication with the fluid conduits 47 and 48 respectively. A second valve 49 similar to the valve 43 controls the passage of fluid in the conduits 47 and 48.

In the operation of the motor, the valves 43 and 49 may be turned to the position as shown in Figure 3. With this arrangement, the pressure supply pump will force fluid through the valve 48, the conduit 47, the passage 45, and into the chamber 31—a. The pressure of this fluid upon the vane 34 will cause the latter to rotate in a clockwise direction as viewed in Figure 3. Since the vane is rigidly connected with the flange 24, the latter will rotate likewise. As the vane 34 thus rotates, fluid within the chamber 31—b will be forced to return to the reservoir via the passage 46 and the conduit 48. Meanwhile, fluid in the chamber 30—b circulates freely thru the pas-

sage 38, conduit 42, valve 43, conduit 41, passage 37 into the chamber 30-a. Thus the turning torque exerted on the flange 24 is directly dependent on the area of that portion of the vane 34 which extends within the chamber 31. 90 degrees rotation of the valve 49 will connect the pressure line 51-a with the line 48, the passage 46, and the chamber 31-b to cause the vane 34 to rotate in a counterclockwise direction as viewed in Figure 3.

In a similar manner, the valves 43 and 49 may be adjusted so that fluid under pressure will be admitted to either chamber 30-a or 30-b and cause either clockwise or counterclockwise rotation of the flange 24, and at the same time free circulation established between the chambers 31-a and 31-b. Since the chamber 30 extends axially farther than the chamber 31, there is a greater vane area subjected to fluid pressure, and therefore, a greater torque transmitted to the flange 24 when the chamber 30 is utilized than when the chamber 31 is utilized.

In another arrangement the valve 43 can be turned to the same position as shown for the valve 49 in Figure 3. With this setting fluid pressure is exerted on the vane 34 in both the chambers 30-a and 31-a so that the total torque transmitted to the flange 24 is the sum of the torques transmitted to the individual vane sections extending across the chambers 30-a and 31-a.

10 I claim:

A fluid motor comprising a cylinder, a transverse partition for dividing said cylinder into separate chambers, an oscillatable shaft disposed centrally of the cylinder and extending through the partition and both of said chambers, a vane in each chamber extending longitudinally thereof, each vane being oscillatable and rigid with the shaft and extending from one end of the 15 chamber to the other in which it is located and also contacting at its free edge with the cylinder wall, an abutment in each chamber extending longitudinally thereof and fixed to the cylinder wall, said abutment being in contact with the shaft, each of said abutments having ports leading through opposite sides thereof to the chamber with which it is associated, a fluid supply for the motor, independently operated valves disposed between the fluid supply and the respective chambers, each valve having ports adapted to be positioned so that fluid may be directed to the chamber with which it is associated at either side of the abutment and exhausted from the other side, and a port for connecting the chamber at opposite sides of the abutment so as to provide a neutral closed fluid 20 25 chamber.

ARTHUR L. PARKER.
